UNITED STATES PATENT OFFICE.

CAMILLE POIRIER, OF DULUTH, MINNESOTA.

PACK-STRAP.

SPECIFICATION forming part of Letters Patent No. 268,932, dated December 12, 1882.

Application filed October 11, 1882. (Model.)

To all whom it may concern:

Be it known that I, CAMILLE POIRIER, of Duluth, in the county of St. Louis and State of Minnesota, have invented a new and Improved Pack-Strap, of which the following is a full, clear, and exact description.

The object of my invention is to provide a new and improved pack-strap for holding and packing articles of clothing, provisions, and other articles which are to be carried in a package on the back.

The invention consists in a bag formed with a flap and provided with shoulder-straps and a head-strap for supporting and carrying the bag on the back. Sliding pads are provided on the shoulder-straps, which are united by a transverse strap.

The invention also consists in a strap on the sack or bag for the purpose of holding an umbrella or sun-shade over the head of the person carrying the sack.

Reference is to be had to the accompanying drawings, forming part of this specification, in which similar letters of reference indicate corresponding parts in all the figures.

Figure 1 is a perspective view of my improved pack-strap, showing the side that is to rest against the back. Fig. 2 is a perspective view of the same, showing the outer side. Fig. 3 shows the manner of using the pack-strap.

A sack or bag, A, which is made of canvas, leather, or any other suitable material, is open at its top and is provided with a wing or flap, B, which rests on the outer surface of the bag and is provided with a series of straps, C, by means of which and buckles D on the sack or bag A the flap can be held to the bag, and the opening of the bag will be closed. A broad head-strap, E, is secured to the bag at the top and on that side which is to rest against the back. The head-strap can be adjusted in length as may be desired, as its ends are secured to buckles secured to the bag or sack A. Two shoulder-straps, F, have their upper ends secured to a piece of leather, G, on the bag A, and the lower ends of the said straps can be secured to the bag by means of buckles H, fastened to the lower corners of the bag on the surface that is to rest against the back. Two straps, I, are provided with end loops, through

which the straps F pass, so that the straps I can be adjusted higher or lower on the straps F. The free ends of the straps I are united by a buckle, J, which permits of adjusting the length of the united straps I according to convenience. The straps F are provided with adjustable or sliding pads K, of leather, which are wider than the straps F for the purpose of distributing the pressure of the straps F and preventing them from pinching the person that is carrying the bundle. On the outer surface of the flap B a loop-strap, M, is secured, which is to be used to hold an umbrella or sun-shade over the head of the person carrying the bundle. Provisions, &c., are placed in the bag A, and a blanket, L, is placed under the flap B, under which it is held in position by means of the straps C. The arms are passed through the loops formed by the straps F, and by means of the straps I the straps F are drawn together sufficiently to prevent the bundle from slipping off the back. The head-strap E is passed over the forehead of the wearer, and is used to assist in carrying the weight of the bundle. The provisions, &c., need not be disturbed if the blanket is to be removed.

Having thus fully described my invention, I claim as new and desire to secure by Letters Patent—

1. The combination, with the bag A, of the shoulder-straps F and the head-strap E, substantially as herein shown and described, and for the purpose set forth.

2. The combination, with the bag A, of the straps F and the sliding pads K, substantially as herein shown and described, and for the purpose set forth.

3. The combination, with the bag A, of the straps F, the sliding pads K, the sliding straps I, and the buckle J, substantially as herein shown and described, and for the purpose set forth.

4. The bag A, provided with the flap B, the straps F, and the strap M on the back of the bag, substantially as herein shown and described, and for the purpose set forth.

CAMILLE POIRIER.
